UNITED STATES PATENT OFFICE.

ELMER E. BUTCHER, OF INTERLAKEN, NEW JERSEY, ASSIGNOR TO MARCONI WIRELESS TELEGRAPH COMPANY OF AMERICA, A CORPORATION OF NEW JERSEY.

RECEIVER OF ELECTRICAL OSCILLATIONS.

1,226,060.

Specification of Letters Patent.

Patented May 15, 1917.

Application filed April 9, 1914. Serial No. 830,593.

To all whom it may concern:

Be it known that I, ELMER E. BUTCHER, a citizen of the United States, and a resident of the town of Interlaken, in the county of 5 Monmouth, State of New Jersey, have invented certain new and useful Improvements in Receivers of Electrical Oscillations, of which the following is a specification.

My invention relates to means for receiving and detecting electrical oscillations, no matter how produced, and may be used to advantage in wireless telegraphy and in various other connections such, for instance, as in wire telegraphy or wire or wireless telephony.

In the drawings hereto annexed I have shown my invention in connection with a wireless telegraph system but, as I have said above, this is only one of the many uses to 20 which it may be put and the drawings should, therefore, be taken as illustrating operative forms my invention may take and not the only forms in which it is capable of use.

25 I have shown in Figure 1 the receiving end of a wireless telegraph system in which 1 is the aerial containing an aerial tuning inductance 2, the aerial being connected to the earth or a suitable capacity at 4. A variable 30 condenser 3 may be used as shown in Fig. 4. This aerial preferably consists of a relatively long horizontal conductor connected to the earth, although this is not necessary to the practice of my invention, since I may use a 35 vertical wire or other form of aerial. The free end of the aerial, being a point most remote electrically from the earthed point 4, and being made a point of maximum potential, is connected to a detector 5. This detector is preferably though not necessarily, 40 a conductive gaseous detector, containing a plurality of elements separated by a conductive gaseous medium. The aerial 1 is preferably connected to a cold element 6 of the detector, which may be in the form of a grid or mesh. This element is preferably interposed between a hot element 7 and a cold element 8. Element 7 may be in the form of a filament which is heated by a battery 9, and element 8 may be in the form of a plate.

45 A local telephone circuit connects elements 7 and 8. This circuit contains a telephone 10 and a battery 11 in series therewith.

50 It should be understood that the detector 55 is not necessarily directly connected to the

aerial, since it may be connected thereto electromagnetically or electrostatically; and I wish to have it understood that when I have used the term "connected" I intend to include all of these equivalent methods. 60

I have illustrated in Fig. 2 the electrostatic coupling, which may comprise plates such as 12 and 13, which may be separated a variable distance.

In Fig. 3 I have shown the electromagnetic 65 coupling, in which 14 and 15 are respectively the primary and secondary of a pair of coupling coils.

I have found in the practice of my invention that it is sometimes useful to connect 70 the hot filament 7 to an inductance having a free terminal such as coil 16. This coil preferably has a large number of convolutions and is adjusted for maximum response by varying the number of its turns. 75

In the operation of my device, the aerial is tuned to the periodicity of the received oscillations or so adjusted as to produce maximum potential at the detector and the constants of the detector circuit are then varied 80 to secure the loudest response in the telephone 10.

What I claim is:

1. In a receiver of electrical oscillations, an aerial grounded at only one end and a 85 detector connected to the opposite end thereof.

2. In a receiver of electrical oscillations, a circuit earthed at only one end and containing means for adjusting to the periodicity of the received oscillations adjacent to the earthed point and detecting means connected to the circuit at a point remote from said means and from the earthed end. 90

3. In a receiver of electrical oscillations, 95 a circuit earthed at only one end and containing means for adjusting to the periodicity of the received oscillations and detecting means connected to the circuit at a point of maximum potential remote from 100 the earthed end.

4. In a receiver of electrical oscillations, a circuit earthed at only one end and containing means for adjusting to the periodicity of received oscillations adjacent to 105 the earthed point and detecting means connected to the circuit at a point of maximum potential remote from the earthed end.

5. In a receiver of electrical oscillations, 110 a circuit in the form of an extended elevated

- horizontal conductor earthed at only one end and containing means for adjusting to the periodicity of received oscillations and detecting means connected to the circuit at 5 a point remote from the earthed end.
6. In a receiver of electrical oscillations, a circuit in the form of an extended elevated horizontal conductor earthed at only one end and containing means for adjusting to 10 the periodicity of received oscillations adjacent to the earthed point and detecting means connected to the circuit at a point of maximum potential remote from the earthed end.
- 15 7. In a receiver of electrical oscillations, a receiving aerial connected to the earth at one terminal and at the other terminal to detecting means comprising a plurality of elements separated by a conductive gaseous medium.
- 20 8. In a receiver of electrical oscillations, a receiving aerial connected to the earth at one terminal and containing means for adjusting to the periodicity of received oscillations adjacent to that terminal and at the other terminal to detecting means comprising a plurality of elements separated by a conductive gaseous medium and means for heating one of said elements.
- 25 9. In a receiver of electrical oscillations, a receiving aerial earthed at only one end and containing means for adjusting to the periodicity of received oscillations and detecting means comprising a sealed vessel inclosing a plurality of elements separated by a conductive gaseous medium connected to the circuit at a point of maximum potential 30 remote from the earthed end.
- 25 10. In a receiver of electrical oscillations,

an earthed circuit, a coil having a free terminal and detecting means connected to the coil and to the circuit at a point remote from the earthed point.

11. In a receiver of electrical oscillations, an earthed circuit containing means for adjusting to the periodicity of the received oscillations adjacent to the earthed point, a coil having a free terminal and detecting means connected to the coil and to the circuit at a point of maximum potential 45 remote from the earthed point.

12. In a receiver of electrical oscillations, detecting means comprising a plurality of elements separated by a conductive gaseous medium, means for heating one of said elements, a coil having a free end connected to the heated element, and an earthed circuit 50 connected to one of the cold elements at a point remote from the earthed point.

13. In a receiver of electrical oscillations, detecting means comprising a sealed vessel inclosing a plurality of elements separated by a conductive gaseous medium, means for heating one of said elements, a coil connected to the heated element and having a 55 free end and an earthed circuit containing means for adjusting to the periodicity of the received oscillations adjacent to the earthed point connected to one of the cold elements at a point of maximum potential 60 remote from the earthed point.

In witness whereof I have hereunto signed my name in the presence of two witnesses this 8th day of April, 1914.

ELMER E. BUTCHER.
